UNITED STATES PATENT OFFICE.

GEORGE H. BRONSON, OF CINCINNATI, OHIO, ASSIGNOR TO HIMSELF AND DAVID MILLARD,
OF SAME PLACE.

HYDROCARBON-VAPOR APPARATUS.

Specification of Letters Patent No. 26,458, dated December 13, 1859.

To all whom it may concern:

Be it known that I, GEORGE H. BRONSON, of Cincinnati, in the county of Hamilton and State of Ohio, have invented a new and useful Improvement in Gas-Carbonizers; and I do hereby declare that the following is a full and exact description thereof, reference being had to the accompanying drawings, and to the letters of reference marked thereon, making part of this specification.

The nature of my invention relates to the arrangement of the zigzag passages through the carbonizing or naphthalizing apparatus substantially as hereinafter described.

With reference to the accompanying drawings, Figure 1, is a perspective view of the apparatus, a small portion of the top plate being broken out, and one end removed and shown separately in elevation in Fig. 2. Fig. 3, is a sectional view, showing the arrangement of the corrugations. Fig. 4, is a sectional view showing how wood may be applied as the capillary conducting material.

A ¹ is the case and is divided horizontally into separate apartments or chambers by the division plates B. Any suitable number of these chambers may be formed by means of a corresponding number of plates B. On the upper side of these plates are arranged at equal distances apart the strips C. Through these strips C, are made a suitable number of perforations D, to allow naphtha or other hydrocarbon liquid to flow freely. On one side of each of these plates near the side of the case A is arranged the strip E, not so high as the others so that when the liquid rises so as to flow over them the strips C, will still stand somewhat above the liquid forming upward projecting edges for the gas to pass over. The strips E, have no perforations and the liquid can not pass them till it flows over the tops of them, they are also arranged on one side of the case on alternate division plates and on the opposite side of the case on the intermediate plates. Outside of strips E, perforations are made through the plates B, next to the side of the case on that when the liquid rises on one plate high enough to run over strip E, it will flow down through these perforations into the next apartment. On the under side of plates B, and intermediate between strips C, are arranged the strips F, projecting downward. On these strips and drawn up

between them against plate B, is arranged and secured as shown, a coating of paper or other porous substance suitable to conduct by capillary action the hydrocarbon liquid, forming a series of zigzag passages from side to side of the apparatus, in each of the several chambers thereof, there being arranged and suspended from the roof B of each chamber zigzags of cloth or paper, with intervening strips or joists C resting edge-wise upon the floor thereof, forming together a horizontal zigzag passage for the gases to traverse the chambers.

From the coating of the under sides of plate B, are arranged to hang down into the liquid strips G, of like material which serve as capillary conductors by which said coating becomes saturated with the hydro-carbon fluid from below and which also serve to vaporize the liquid as well as the coating upon the under side of plate B. This vaporizing and capillary conducting material for the strips G, and coating of plates B, may be of paper as shown, or any other fibrous or porous substance as for instance wood, cloth, paper, cotton, sponge &c.

This apparatus is adapted to the purpose of mixing the vapors of naphtha and other hydro-carbon liquids with either air or gas.

The opening J, is for the purpose of introducing the hydro-carbon liquid and the opening K, is for letting it out by a faucet or other means when it has risen to the proper height in the lower apartment. Opening H, is for the admission of the gas or air to be carbonized and opening I, for its exit after being mixed with the vapors of the hydro-carbon liquid. The case can be made of any suitable material to contain the liquids and gases to be used.

Having thus described the construction of my improvement I will proceed to explain the operation.

The opening H, being connected with the supplying gas pipe and the opening I, with the delivery pipe, the naphtha or other hydro-carbon liquid is poured in at the opening J, the upper plate B, thereby is covered with it and it rises until it flows over strip E, and down through the perforations L, into the next apartment filling that in like manner to the top of strip E, and then flowing down through perforations M, into the next apartment and so on till all are in like manner supplied and the lower apart-

ment filled up to opening K, out of which it begins to flow by the faucet or other discharging device, then the supply at J, is checked. The apparatus being thus supplied with the liquid the gas or air is let in at opening H, (which may be arranged on the opposite side) and passes upward through openings N, into the apartment next above then in a zigzag passage formed by the alternating of the corrugations before described it finds its way across the case to the openings or perforations M, and passes through them into the next apartment above and so on passing from side to side through the zigzag passages and amid the evaporation from above and below, of the hydro-carbon liquid becomes suitably impregnated therewith and passes out into the delivery or distributing pipe at I.

Thus having described the construction

and operation of my improvement. I would remark that I do not claim the use of absorption surfaces in the process of carborizing or naphthalizing illuminating gases, nor do I claim forming zigzag passages through 25 a naphthalizing apparatus. But

What I claim as my invention and desire to secure by Letters Patent is—

The arrangement and combination of the zigzag folded surfaces extended over the 30 projecting edges, F, with the projecting edges of E, C, C, C, C, and so forth in each of the several cells or chambers of the impregnating apparatus substantially in the manner and for the purpose herein set forth. 35

GEO. H. BRONSON.
